United States Patent Office

Des. 208,926
Patented Oct. 17, 1967

208,926

SOD ROLLER

Kenneth B. Dice, 218 5th St., and Richard M. Maas,
1303 Jackson St., both of Millard, Nebr. 68043

Filed July 27, 1966, Ser. No. 3,227

Term of patent 14 years

(Cl. D40—1)

Fig. 1

Fig. 2

Fig. 3

Fig. 5

Fig. 4

FIGURE 1 is a top plan view of a sod roller showing our new design.

FIGURE 2 is an elevational view taken from one side thereof.

FIGURE 3 is a front elevational view thereof.

FIGURE 4 is a rear elevational view thereof.

FIGURE 5 is an elevational view taken from the side opposite that shown in FIGURE 2.

We claim:

The ornamental design for a sod roller, as shown.
